ELECTRIC CABLE

Irving T. Fauoett, Westerleigh, N. Y., assignor
to General Cable Corporation, New York, N. Y.,
a corporation of New Jersey

Application June 28, 1932, Serial No. 619,649

7 Claims. (Cl. 173—266)

This invention relates to insulated electric cables, and more particularly to shielded cables. It is an object of the invention to provide improved cable constructions. Other objects and advantages of the invention will appear herein-after.

An illustrative embodiment of the invention selected merely for descriptive purposes is shown in the accompanying drawing, in which:

Fig. 1 is a longitudinal elevation of a single conductor cable with portions of the sheath, shielding layers and insulation removed to disclose the invention more clearly;

Fig. 2 is an end elevation of the cable shown in Fig. 1;

Fig. 3 is a longitudinal elevation of a three conductor cable with portions of the sheath, binding tape, shielding layers and insulation removed to disclose the invention more clearly; and

Fig. 4 is an end elevation of the cable shown in Fig. 3.

It has been proposed heretofore to provide one or both surfaces of the wall of insulation surrounding a cable conductor with a thin electrostatic shield for purposes of distributing electrical stress within the insulation, and limiting the electrical stress to the wall of insulation, thereby preventing or reducing ionization at the surface of the insulation.

The electrostatic shield ordinarily takes the form of a metal ribbon or metallized paper tape helically wound about the conductor before the insulation is applied, or over the conductor insulation, with the adjacent turns of the shielding ribbon or tape lying side by side. In practice, adjacent turns of the shielding strip are spaced apart slightly. It is practically impossible to wind the shielding strip in place with adjacent edges exactly abutting, and with a metal ribbon it is desirable to have a slight spacing between adjacent turns to permit bending of the cable with a minimum danger of buckling of the shielding strip and damage to the cable insulation.

The shielding layer desirably is very flexible so as to conform closely to the surface of the insulation at all times. Otherwise spaces would be formed between the shielding layer and the cable insulation when the cable is handled, and such spaces would be under electrical stress during operation of the cable. Ionization in these spaces would injure the cable insulation and eventually might result in breakdown of the cable.

In the known constructions the shielding is not perfect because small ionizable spaces are present between adjacent turns of the shielding strip

where the turns lie side by side, and at the inner edge of the shielding strip if the adjacent turns are overlapped. These spaces ordinarily are very small, but it has been found that the dielectric strength of an insulated cable is substantially increased if these unshielded spaces are eliminated or reduced in size.

According to this invention insulated cable constructions are provided in which one or both surfaces of the insulating wall surrounding the cable 10 conductor may be completely shielded, and in which ionizable spaces at the surfaces of the conductor insulation are reduced to a minimum.

Referring first to Figs. 1 and 2, there is shown by way of illustration a single conductor cable in 15 which both the inner and outer surfaces of the insulating wall are shielded. The conductor 11 is a stranded conductor, and it will be seen from Fig. 2 that small valleys 12 exist on the outer surface of the conductor between adjacent conduct- 20 ing strands. If the insulating wall were applied immediately over the stranded conductor, these small spaces 12 would be under electrical stress when the cable is in operation.

In accordance with this invention the spaces 12 25 are shielded by wrapping helically about the conductor a conducting ribbon 13 whose adjacent turns lie side by side, and simultaneously therewith an overlapping conducting tape 15. This ribbon 13 should have a fairly high tensile 30 strength, and desirably is a thin metal tape, conveniently copper. Desirably the metal ribbon is perforated as at 14 to reduce electrical losses due to currents induced therein. It will be apparent that the helically wound ribbon 13 shields to a 35 large extent the spaces 12, but that if it were not for the overlapping conducting tape 15 there would be unshielded spaces between adjacent turns of the ribbon.

The ribbon 13 is substantially incompressible, 40 and is fairly stiff, so that if adjacent turns were overlapped to eliminate the spaces between turns the flexibility of the cable would be lessened, and there would be a small unshielded helically extending space adjacent the overlapping edge of 45 the ribbon, which space would not be completely filled by insulation applied over the shielding layer. Furthermore, in such a construction bending of the cable might result in buckling of the shielding strip, which would injure the cable 50 insulation or enlarge the existing unshielded spaces.

As the metal ribbon 13 and conducting tape 15 are helically wrapped on the conductor, the tape 15 overlaps and extends beyond one edge of the 55

metal ribbon 18. Therefore, each turn of the spirally wrapped tape 16 extends between adjacent turns of the metal ribbon 18, underlying one turn of the metal ribbon and overlying an adjacent turn of the metal ribbon.

The tape 16 desirably is somewhat more flexible than the metal ribbon 18, and conveniently will be a fibrous tape which has been treated with conducting material. Merely by way of illustration, the tape 16 may be a metallized paper tape, or a cloth tape which has been treated with a mixture containing casein and lamp black. The tape 16 is more flexible than the metal ribbon 18 and is relatively compressible. As a result, the tape 16 conforms readily to its position extending between and underlying and overlying adjacent turns of the metal ribbon.

Since the tape 16 is electrically conducting, the spaces between adjacent turns of the metal ribbon 18 are completely shielded. Although in the illustrative embodiment the tape 16 is approximately the same width as the metal ribbon 18, and therefore will only partially underlie and partially overlie adjacent turns of the metal ribbon, obviously the width of the tape 16 might be varied so as to underlie and overlie greater or lesser portions of the metal ribbon.

Over the shielding layer formed by the conducting strips 18 and 16 is applied the regular conductor insulation 10. In high tension cables this insulation ordinarily takes the form of a plurality of overlying layers of helically wrapped paper tape, the adjacent turns of the tape in each layer lying side by side. Over the outer surface of the insulating wall 16 is applied a shielding layer similar to that applied directly over the conductor. In the drawing, this shielding layer comprises the helically wrapped metal ribbon 17 and the helically wrapped, overlapping conducting tape 18. Over this shielding layer is the cable sheath 28, which in high tension cables ordinarily takes the form of a lead tube.

Figs. 3 and 4 disclose the invention as applied to three conductor cable. In the illustrative showing the conductor insulation is shielded only on its outer surface. It will be obvious that the insulation could also be shielded on its inner surface in the same manner as is shown for single conductor cable.

Three similar conductors 21 are each enclosed in a wall 22 of insulation. Over each of the insulating walls 22 is applied a shielding layer comprising the overlapping helically wrapped metal ribbon 23 and conducting tape 24. The three insulated and shielded conductors are cabled together, and the valleys between the conductors conveniently are rounded out with filler material 25. Desirably the insulated conductors and the fillers are held in assembled position by means of a helically wrapped binding tape 26. This binding tape conveniently is a thin steel or bronze tape, and is applied simultaneously with an overlapping tape 27 which may be an insulating tape, or which may be a fibrous tape treated with conducting material. If the tape 27 is a conducting tape, the electrical resistance between the shielding layers overlying each insulated conductor and the cable sheath 28 will be reduced. Over the binding strip 26 is the cable sheath 28, which ordinarily would be of lead or a lead alloy in cable of the type shown.

It will be apparent that this invention provides shielded cable in which ionizable spaces adjacent the surface of the cable insulation are substantially eliminated. Tests have shown that

cable constructed according to this invention has greatly improved dielectric strength as compared to cables heretofore known. In addition to the improvement in dielectric strength, such cable would be expected to have a much longer life.

The foregoing description of certain specific embodiments of the invention is illustrative merely, and is not intended as defining the limits of the invention.

I claim:

1. An electric cable comprising, in combination, a conductor, a wall of insulation surrounding the conductor, an electrostatic shield overlying the insulation, said shield comprising a helically wound metallic ribbon whose turns are positioned side by side and a relatively more flexible fibrous tape treated with conducting material wound on simultaneously with said metallic ribbon so that a turn of the fibrous tape underlies one turn of the ribbon and overlies an adjacent turn of the ribbon, and a sheath enclosing the insulated conductor.

2. An electric cable comprising, in combination, a conductor, a wall of insulation surrounding the conductor, an electrostatic shield interposed between the conductor and the insulation, said shield comprising a helically wound metallic ribbon whose turns are positioned side by side and a relatively more flexible fibrous tape treated with conducting material wound on simultaneously with said metallic ribbon so that a turn of the fibrous tape underlies one turn of the ribbon and overlies an adjacent turn of the ribbon and a sheath enclosing the insulated conductor.

3. An electric cable comprising, in combination, a conductor, a wall of insulation surrounding the conductor, an electrostatic shield immediately adjacent one surface of the wall of insulation, said shield comprising a metallic ribbon and a relatively more flexible fibrous tape treated with conducting material helically wound together with the tape interlocked with the ribbon in lapping relation, and a sheath enclosing the insulated conductor.

4. An electric cable comprising, in combination, a conductor, a wall of insulation surrounding the conductor, a sheath enclosing the insulated conductor, and an electrostatic shield immediately adjacent one surface of the insulating wall, said shield comprising a helically wound metallic ribbon, the turns of which are positioned side by side, and a helically wound, metallized fibrous tape, said metallized fibrous tape being more flexible than the metallic ribbon and each turn of the tape overlying one turn of the ribbon and underlying an adjacent turn of the ribbon.

5. An electric cable comprising, in combination, a conductor, a wall of insulation surrounding the conductor, a sheath enclosing the insulated conductor, and an electrostatic shield immediately adjacent one surface of the insulating wall, said shield comprising a helically wound metallic ribbon, the turns of which are positioned side by side, and a helically wound, metallized fibrous tape more flexible than the metallic ribbon wound on simultaneously with the ribbon, said tape being interlocked with the ribbon and extending transversely beyond one longitudinal edge of the ribbon to overlap an adjacent turn of the ribbon.

6. An electric cable comprising, in combination, a conductor, a wall of insulation surrounding the conductor, a sheath enclosing the insulated conductor, and an electrostatic shield immediately adjacent one surface of the insulating

wall, said shield comprising a metal ribbon and a relatively more flexible metallized fibrous tape helically wrapped about the conductor with a turn of the metallized fibrous tape underlying one turn of the metal ribbon and overlying an adjacent turn of the metal ribbon.

7. An electric cable comprising, in combination, a conductor, a wall of insulation surrounding the conductor, a sheath enclosing the insulated conductor, and an electrostatic shield im-

mediately adjacent one surface of the insulating wall, said shield comprising two conducting strips, one of which is relatively stiff and the other of which is relatively more flexible, simultaneously helically wound about the conductor with the turns of the relatively stiff strip side by side and with the turns of the more flexible strip extending between and underlying and overlying adjacent turns of the relatively stiff strip.
